TELEMETER SYSTEM

George S. Lunge, Scotia, N. Y., assignor to General Electric Company, a corporation of New York

Application February 10, 1944, Serial No. 521,891

7 Claims. (Cl. 179—2.5)

The present invention relates to a telemeter system having a channel alternatively usable for voice or telemetering.

An object of my invention is to provide an improved arrangement for disconnecting the telemetering equipment to permit use of the channel for voice and for subsequently reconnecting the telemetering equipment.

My arrangement is especially advantageous when the telemeter transmitter is at an unattended station and voice communication is desired between two other stations.

The novel features which I believe to be characteristic of my invention are set forth with particularity in the appended claims. My invention itself, however, both as to its organization and method of operation, together with further objects and advantages thereof, may best be understood by reference to the following description taken in connection with the accompanying drawing in which the single figure is a diagram of a system embodying my invention.

Referring to the drawing there is shown a transmission line 1 connecting a plurality of stations, three of which are shown designated by the letters A, B, and C. At each of the stations are a carrier current transmitter 2 and receiver 3 with which are associated protective relays 4 which assume control during faults and cause the transmission of the carrier current relaying signals necessary to protect the system. At two or more of the stations is telemeter equipment of the repetitive impulse type in which the telemetering is effected by the frequency or duration of the carrier impulses. A telemeter transmitter 5 is illustrated at station A and telemeter receivers 6 are illustrated at stations B and C, each being connected to the associated carrier transmitter or receiver through a normally closed relay 7. At each of the stations is a telephone handset 8 connected to the station transmitter and receiver. While the handsets are at all times effective to receive and to transmit when a button 11 in the handset is depressed, during telemetering the superimposed telemetering impulses as a practical matter make voice communication impossible. It is therefore desirable that the voice and telemetering equipment be alternatively usable.

This is accomplished by an instantaneous relay 9 connected to the output of each receiver which picks up when carrier signals are being received and deenergizes a normally open time delay dropout relay 10 in series with the associated telemeter connecting relays 7. The time delay of the

relay 10 is greater than the maximum length of the telemetering impulses so the relay does not drop out during telemetering.

When voice communication is desired between two stations, the button 11 at the calling station handset is closed for an interval greater than the longest telemetering impulse and is thereafter opened and closed in accordance with a prearranged code. During each closure of the button, the associated transmitter transmits a carrier impulse. The first impulse, being of greater duration than the telemetering impulses, energizes the relays 9 long enough to permit the relays 10 to drop out and energize the relays 7 to disconnect the telemetering equipment and to close contacts 12, in circuit with call relays 13 through contacts 16 closed by relays 9 during the reception of carrier signals. The call relay contacts 18 are in series with bell operating magnets 14 through hook switches 15 for the handsets 8. At the calling station, the handset is removed from the hook switch before calling so the associated bell operating magnet 14 is not energized. When the calling station handset is first lifted from its hook switch, the telemetering impulses can be heard in its receiver. To call another station the button 11 at the calling station handset is held closed until the telemetering impulses disappear, indicating the disconnection of the telemetering equipment and the actuation of the bell operating magnets 14 at other stations where the handsets are on the hook switches to cause a single stroke on the station call bells 17. Thereafter the button 11 can be opened as rapidly as desired and closed in accordance with the calling code, each closure of the button causing an additional stroke on the bells. The bell at the called station is deenergized when the call is answered by lifting the handset off the hook switch. This permits voice communication between the stations. At other stations the bells will be energized at each change in the direction of voice communication, indicating the use of the telemetering channel for voice communication. This is not objectionable so long as the code calls are more than one bell stroke. The fact that the use of the telemetering channel for voice is indicated at other stations tends to discourage long conversations.

To prevent reconnection of the telemetering equipment during normal gaps in the conversation (and during calling of other stations by closing and opening the button 11), the call relays 13, which are energized while the telemetering equipment is disconnected through contacts 12

and 16 whenever signals are being received, close the contacts 18, energizing time delay drop-out relays 19 which until drop-out maintain holding circuits through contacts 20 for the telemeter disconnect relays 7. The telemeter disconnect relays 7 are deenergized to reconnect the telemetering equipment only upon drop-out of the relays 19. The drop-out time can conveniently be greater than any gap in the conversation or in the code calling. The drop-out time of the relay 19 at the station having the telemeter transmitter is preferably one or two seconds greater than the drop-out time of the relays 19 at the other stations. This is to avoid the possibility of telemeter impulses being applied to the channel before all of the other relays 19 have dropped out. If any of the other relays 19 have not dropped out, the telemeter impulses would operate the station bells.

While I have shown particular embodiments of my invention, it will be understood that many modifications may be made without departing from the spirit thereof, and I contemplate by the appended claims to cover any such modifications as fall within the true spirit and scope of my invention.

What I claim as new and desire to secure by Letters Patent of the United States is:

1. In a telemeter system having a single channel to which are connected telemeter and voice equipment, the telemeter equipment being of the repetitive impulse type, means responsive to a signal of greater duration than the telemeter impulses for disconnecting the telemeter equipment to permit use of the voice equipment, and means responsive to the interruption of signals for reconnecting the telemeter equipment.

2. In a telemeter system having a single channel to which are connected telemeter and voice equipment, the telemeter equipment being of the repetitive impulse type, a disconnect relay for the telemeter equipment, a time delay relay responsive to a signal of greater duration than the telemeter impulse for operating the disconnect relay to permit use of the voice equipment, a holding circuit for the disconnect relay established upon its operation and including a time delay relay operated to break the holding circuit in response to interruption of signals.

3. In a telemeter system having a plurality of stations each equipped with a carrier current transmitter and receiver, a telemeter channel of the periodic signal type having a telemeter transmitter at one of said stations associated with the carrier transmitter, and a telemeter re-

ceiver associated with the carrier receiver at another station, a voice channel utilizing said carrier current transmitters and receivers, means responsive to carrier current signals of greater duration than the telemeter signals for disconnecting the telemeter channel, a call circuit for the voice channel rendered effective upon disconnection of the telemeter channel, and means responsive to interruption of the voice signals for reestablishing the telemeter channel.

4. In a telemeter system having a single channel to which are connected telemeter and voice equipment, signal responsive means for disconnecting the telemeter equipment, a call circuit for the voice equipment rendered effective by disconnection of the telemeter equipment, and time delay means responsive to the absence of signals for a predetermined time for reconnecting the telemeter equipment.

5. In a telemeter system having a single channel to which are connected telemeter and voice equipment, a circuit for transmitting call signals through the channel for the voice equipment, means responsive to said call circuit signals for disconnecting the telemeter equipment, and time delay means responsive to the interruption of signals in the channel for reconnecting the telemeter equipment.

6. In a telemeter system having a single channel interconnecting several stations and to which are connected telemeter equipment of the repetitive impulse type and carrier current voice equipment, means responsive to a signal in the channel of greater duration than the telemeter impulses for disconnecting the telemeter equipment to render the channel usable for voice communication, means responsive to an interruption of signals in the channel for an interval greater than the normal gap in conversation for reconnecting the telemeter equipment to the channel, and station calling means operative to send calling signals through said channel spaced apart less than said interval.

7. In a telemeter system having a single channel to which are connected telemeter and voice equipment, said telemeter equipment being normally connected to said channel, a circuit for transmitting voice equipment call signals through the channel during connection of said telemeter equipment to said channel, means responsive to said signals for disconnecting the telemeter equipment, and time delay means responsive to the absence of signals for a predetermined time for reconnecting the telemeter equipment.

GEORGE S. LUNGE.
